UNITED STATES PATENT OFFICE.

FRANK G. REYNOLDS, OF CHICAGO, ILLINOIS.

DESIGN FOR A FRAME FOR KNIFE-SHARPENERS OR GLASS-CUTTERS.

SPECIFICATION forming part of Design No. 34,761, dated July 9, 1901.

Application filed May 20, 1901. Serial No. 61,198. Term of patent 7 years.

To all whom it may concern:

Be it known that I, FRANK G. REYNOLDS, a citizen of the United States, residing at Chicago, in the county of Cook and State of Illinois, have invented and produced a new and original Design for the Frame of a Knife-Sharpener and Glass-Cutter, of which the following is a specification, reference being had to the accompanying drawing, forming a part thereof.

This design relates to the configuration of the frame of a knife-sharpener and glass-cutter.

The accompanying drawing is a perspective view of a frame embodying my design.

The leading or material feature of my design consists of a base-plate, an upright bracket-plate rising from one end of the base-plate, a pair of central spurs or projections extending upwardly from said bracket-plate, a similar upward projection arranged on one side of said central projections, and an up-

ward projection arranged on the bracket-plate at the opposite side of said central spurs and having a horizontal arm which extends 25 outwardly therefrom and terminates in a pair of jaws.

Referring to the drawing, A is the base-plate of the frame, and B the upright bracket-plate.

c c are the upright central spurs of the bracket-plate, and c' is one of its lateral projections. d is the other lateral projection, and d' its forked outwardly-extending arm. e is an aperture arranged in the base-plate A. 35

What I claim is—

The design for the frame of a knife-sharpener and glass-cutter, substantially as herein shown and described.

Witness my hand this 18th day of May, 1901. 40
FRANK G. REYNOLDS.
